DESIGN FOR A RECTIFIER HOUSING

Warren S. Master, Rutherford, N. J., assignor to
Federal Telephone and Radio Corporation,
New York, N. Y., a corporation of Delaware

Application December 4, 1944, Serial No. 116,695

Term of patent 14 years

(Cl. D26—15)

To all whom it may concern:

Be it known that I, Warren S. Master, a citizen of the United States, residing at 29 Carlton Place, Rutherford, Bergen County, State of New Jersey, have invented a new, original, and ornamental Design for Rectifier Housing, of which the following is a specification, reference being had to the accompanying drawing, forming part thereof.

Fig. 1 is a perspective view of a rectifier housing, showing my new design;

Fig. 2 is a perspective view of the same rectifier housing, seen from the other side; and

Fig. 3 is a top plan view of the same rectifier housing.

I claim:

The ornamental design for a rectifier housing, as shown.

WARREN S. MASTER.
